(57) **CLAIM**

The ornamental design for a charging station as shown and described.

DESCRIPTION

FIG. 1 is a front perspective view of a charging station showing my new design;

FIG. 2 is an enlarged front perspective view of a portion of FIG. 1;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The dash-dot-dash broken lines in FIGS. 1 and 2 illustrate the bounds of the enlargement. The dash-dot-dash broken lines form no part of the claimed design. The dash-dot broken lines depict portions of the charging station that form no part of the claimed design.
